UNITED STATES PATENT OFFICE

2,461,674

CENTRIFUGE APPARATUS FOR OBTAINING
BLOOD PLASMA

William Aronson, New York, N. Y.

Application July 25, 1944, Serial No. 546,548

7 Claims. (Cl. 233—28)

1

This invention relates to a method of and apparatus for separating plasma from the red cells of blood and for reinfusing the red cells into the donor of the blood.

It has been determined that blood donations made for obtaining blood plasma can be made more frequently than was previously the case if the red cells of the blood are returned to the donor after the separation of the blood plasma from the donated blood. This enables more blood plasma to be obtained within the same period of time from the same donor that was heretofore possible, without impairing the health or well-being of the donor. Therefore, in order to accomplish that result in a practical way it is highly desirable, if not necessary, to effect the separation of the blood plasma from the donor's blood and to return the red cells to the donor within a short period of time so that donors may be encouraged to give frequent blood donations for plasma without being subjected to too much inconvenience or loss of time. More specifically, in accordance with the present invention provision is made for performing all of the necessary operations, namely, taking the blood from the donor, separating the blood plasma from the donated blood, and reinfusing the red cells into the donor, all within say about thirty minutes or less, also, pursuant to the present invention, the needle through which the blood is drawn from the donor can remain in position in the donor's arm after the blood donation is completed, ready for use in reinfusing the red cells immediately after the separation of the plasma.

Therefore, a prime object of the present invention is to provide a method of an apparatus for effecting a rapid separation of blood plasma from the donor's blood and for quickly and easily reinfusing the red blood cells into the donor. Another object of the invention is to provide apparatus which can be properly sterilized and kept sterile throughout the process of obtaining the blood from the donor, separating the plasma therefrom, and reinfusing the red cells into the donor.

A further object of the invention is to obtain as high a yield as possible of the blood plasma from each blood donation while at the same time enabling the process to be performed quickly so

2

that the red cells can be infused into the donor within a short time after the blood donation is made.

The above and other objects, features and advantages will be fully understood from the following description considered in connection with the accompanying illustrative drawings.

In the drawings:

Fig. 1 is a view of apparatus embodying the present invention and illustrates the condition of the apparatus at the time the blood is taken from the donor, the centrifuge-vessel being shown in vertical section;

Fig. 2 is a sectional view on the line 2—2 of Fig. 1;

Fig. 3 is a side view, in elevation, of the apparatus including auxiliary parts for removing the blood plasma and red cells as separate constituent volumes into separate receptacles;

Fig. 4 is a sectional view on the line 4—4 of Fig. 3;

Fig. 5 is a sectional view on the line 5—5 of Fig. 3.

Referring now to the drawings in detail, the apparatus embodying the present invention comprises a centrifuge-vessel 10 which, as here shown, is preferably in the form of flask made of metal. Said vessel removably mounted on a rotary disk or plate 12 which is fixed to and rotatable by the shaft 14 of an electric motor M. Centrifuge-vessel 10 comprises a conical side wall 16 in fluid tight relation with the bottom 18 of the vessel. Said bottom 18 has a central depressed portion 20 forming a well 22 and the annular part 24 of bottom 18 which surrounds well 22 slopes downwardly toward said well, so that any small quantity of liquid in the vessel accumulates in the well. The disk 12 on which the centrifuge-vessel 10 is mounted is provided with a central depressed part or well 26 to receive the well forming part 20 of the vessel 10 and further provides convenient means for centering the vessel 10 with respect to the axis of rotation, it being understood that well-forming part 20 of the vessel has an accurate removable fit in well-forming part 26 of plate 12. The bottom 18 of vessel 10 is provided with a laterally extending peripheral flange 28 having a plurality, here shown as three, circumferentially spaced open-end slots 30 in which the shanks of swivel

bolts 32 fastened to plate 12 are removably received for engagement by companion knurled nuts 34 for securely fastening the vessel 10 to the rotary plate 12. Said plate can be secured to the motor shaft 14 in any suitable way but as here shown rotary plate 12 is provided with a depending collar 36 which is fixed to shaft 14 by a cross pin 38 and by a set screw 40.

Vessel 10 is provided with an upper cylindrical portion 42 integral with conical side wall 16 and terminating at its upper edge in an opening to receive the cylindrical peripheral continuous skirt 44 of a cap 46, said cap having a peripheral flange 48 which engages or seats on the top peripheral edge 50 of cylindrical part 42 of vessel 10. A pair of spring clips 52 are fixed to the cylindrical part 42 and releasably engage the edge of flange 48 of cap 46 for holding the latter releasably in position. It will be understood that skirt 44 has a snug fit with the inner cylindrical surface of part 42 of vessel 10 to provide a fluid tight closure for said vessel. Cap 46 is provided with a guide tube 54 for the float-operated rod indicator 56, the float which is connected to said rod being indicated at 58. The upper portion of indicator rod 56 projects through an opening in the top of cap 46 and is enclosed within a glass or other transparent housing 60 having a fluid tight connection with cap 46. Housing 60 is preferably calibrated as shown in Fig. 3 to serve as a dial indicator for the upper end of rod 56. A tube 62 is fixed to the top of cap 46 and depends therefrom into vessel 10 when the cap is in position. Said tube communicates with the interior of vessel 10 and with a fitting 64 secured to cap 46 at the outer side thereof. A compressible bulb 66 for creating a partial vacuum in vessel 10 at the time the donor's blood is received in said vessel directly from the donor as hereinafter more particularly explained, is connected to the fitting 64 by a rubber tubing 68 and a nipple 70 which is carried by fitting 64. The rubber tubing 68 contains cotton 71 or other air filtering material to provide an air filter for vessel 10 after the bulb 66 is removed from the apparatus. It is convenient to remove bulb 66 from the apparatus by cutting tube 68 between its ends as indicated by the dotted line 72, leaving a portion 68a of tube 68 in position on fitting 64 of cap 46 as shown in Fig. 3 and filled with cotton or other air filtering material 71, thus providing the vessel 10 with an air filter after the bulb 66 is removed, so as to prevent the entrance of bacteria into the vessel.

Vessel 10 is provided with a plurality of circumferentially spaced vertical partition plates 74 (Figs. 1 and 4) which extend vertically downwardly from the upper end of conical wall 16 to a short distance from the bottom 18 of the vessel. The outer ends of said plates 74 are fixed to the inner surface of conical wall 16 and the inner ends of said plates are fixed to a central tube 76 which is disposed axially of vessel 10 and extends vertically from the upper ends of said plates but terminates at its lower end 78 above the lower edges 80 of said plates. A center tube 82 is fixed to and depends from the top of cap 46 and registers with tube 76 of the vessel 10, the lower end of tube 82 seating on the upper end of tube 76 when cap 46 is in position, so that tubes 78 and 82 form in effect a continuous tube extending downwardly from cap 46. A tube 84 is carried by cap 46 in movable relation thereto and is positioned within tubes 82 and 84, having a sliding frictional fit with tube 82. Said

5 tube 84 projects through an opening 86 in cap 46 in fluid tight relation therewith and is provided with an outer nipple 88 having a flange 90 which engages the top of cap 56 for limiting the inward movement of tube 84. A resilient rubber closure cap 92 fits removably on nipple 88.

10 As shown in Fig. 1 a hollow needle 94 is projected through the closure member or cap 92 into tube 84 and is connected by flexible rubber tubing 96 to the needle (not shown) which is projected in the usual way in the vein in the donor's arm for obtaining the latter's blood donation. Tubing 96 is provided with a glass or other transparent insert so that the flow of blood can be observed. While blood is flowing from the donor 15 through tubing 96 and needle 94 into vessel 10, bulb 66 is operated to produce a partial vacuum in vessel 10 to induce the flow of blood from the donor into said vessel. In order to prevent coagulation of the blood in vessel 10, a suitable quantity of an anti-coagulant, for example, a 2.5 solution of sodium citrate is placed in the vessel for the mixture therewith of the blood received in the vessel from the donor. The usual blood donation 20 consists of about 500 cc. and this is received directly from the donor in vessel 10 in which it is mixed with about 100 cc. of the sodium citrate solution. Accordingly, when the gage rod 56 rises to the 600 cc. mark on housing cap 60, the 25 taking of blood from the donor is terminated. It will be understood that at the time of the blood donation, vessel 10 need not be positioned on plate 12 but can be and preferably is removed from plate 12 to a position conveniently near the donor. After the blood from the donor is received in vessel 10, needle 94 is removed through cap 92, the latter remaining in position on the nipple 88 and sealing the inlet opening of the vessel against bacteria or other foreign material. 30 Likewise, after the blood is taken from the donor, the bulb 66 is removed by cutting the tubing 68 as described above, and the vessel 10 is thus provided with an air filter 68a.

35 After the usual quantity of blood, ordinarily about 500 cc., is taken from the donor and received in vessel 10, the tubing 96 is removed from the outlet end of the needle in the donor's arm without, however, removing said needle. The tourniquet which was previously applied to the donor, as in the usual method of blood donation, is removed, and a stylet is introduced into the needle while the latter remains in position in the donor, said stylet serving to fill the passage of said needle, thereby to prevent blood 40 from clotting in said passage. After the blood given by the donor is treated as hereinafter described to remove the plasma therefrom, the residual red cells together with a suitable quantity of saline solution added to and mixed with the red cells are reinfused into the donor. In the reinfusion process, the stylet is removed from the needle and the end of a tube leading from a bottle or other receptacle containing the red cells and the saline solution is connected to the needle 45 and the receptacle is positioned so that the mixture of red cells and saline solution can flow from said receptacle to and through the needle into the donor.

50 In order to separate the plasma from the red cells in the blood received in vessel 10, the blood is first centrifuged in said vessel and for that purpose vessel 10 is mounted on rotary plate 12 of the centrifuge and secured thereto by means of the bolts 32 as described above. It will be understood that bulb 66 and needle 94 are re-

moved from cap 46 before the vessel 10 is rotated for centrifuging the blood in said vessel; preferably, said bulb and needle are removed before the vessel 10 is mounted on plate 12. Needle 94 is removed without removing closure cap 92 and since the latter is formed of resilient rubber, the aperture formed when the needle was projected through the cap automatically closes and seals itself when the needle is removed. The self-sealing cap 92 and the filter 68a (Fig. 3) formed as described above prevent the entrance of bacteria into vessel 10 and provide efficient means to accomplish the quick removal of said bulb and the needle 94 while maintaining the sterile condition of the blood in vessel 10.

Vessel 10 mounted on plate 12 is rotated at high speed, say about 7000 R. P. M., to centrifuge the blood in said vessel. While the time of the centrifuging operation may vary, we have found that after centrifuging the blood for about ten to fifteen minutes, a high yield of plasma is obtained. Due to the centrifugal action the plasma and red cells separate in vessel 10 and when the rotation of said vessel is stopped the red cells and plasma stratify in vessel 10 with the plasma above the red cells in said vessel. The plasma and red cells are now in such condition that the plasma and red cells can be obtained in separate constituent volumes, so that the red cells can be reinfused into the donor, thus enabling plasma to be procured substantially without significant loss to the donor of the red cell value of the donor's blood.

The presently preferred method of and apparatus for separating the plasma and red cells into separate constituent volumes will now be described:

As illustrated in Fig. 3, containers, such as bottles 100 and 102, preferably having volume scale graduations, as indicated, are provided to receive the plasma and red cells, respectively, from vessel 10. Said bottles 100 and 102 are connected to a Y-tube 104 by flexible tubing 106 and 108, respectively, said tubing being provided with pinch clamps 110 and 112, for releasably closing the passages through said tubing. Each of said bottles 100 and 102 is provided with a compressible air-exhaust bulb 114 for producing a partial vacuum in the companion bottle. A needle 116 is connected to the Y-tube 104 by a flexible tubing 118. Said needle is projected through cap 92 into tube 84 of centrifuge vessel 10. In the operation of removing the plasma from vessel 10, the tube 84 is positioned so that its lower end is above the level of the layer of blood cells, said level being indicated by the dotted line C in Fig. 3, and the level of plasma above said cells being indicated by the dotted line P. Tube 84 is held releasably in raised position, so that its lower end 120 is positioned above the layer of red cells as just described, by a removable split sleeve 122, or in any other suitable way, said sleeve being disposed between the top of cap 46 and the flange 90 of nipple 88 at the upper end of tube 84.

For removing the plasma from vessel 10, pinch clamp 112 being tightened to close tubing 108 and pinch clamp 110 being retracted so that tubing 106 is open, bulb 114 of plasma bottle 100 is operated to exhaust air from said bottle to produce a partial vacuum therein so that the plasma flows by suction from vessel 10 upwardly into tube 84 and from the latter through needle 116, Y-tube 104, and tubing 106 into said bottle. The scale on said bottle provides convenient means for

indicating when the plasma is substantially all removed from vessel 10 to bottle 100. In this connection, it will be understood that the volumetric proportions of plasma and red cells are approximately equal and that since, as in the average case, the quantity of the blood donation is 500 cc. which is added to about 100 cc. of anti-coagulant provided in vessel 10, the volume removed from vessel 10 to plasma bottle 100 in the plasma removal operation is about 300 cc. which is about one half of the total volume of blood and anti-coagulant in vessel 10 at the conclusion of the blood taking operation. Accordingly, when the scale on bottle 100 indicates that a volume of about 300 cc. has passed from vessel 10 into said bottle, the plasma removal operation is terminated and the red-cell removal operation is begun.

For removing the red cells from vessel 10 into bottle 102, tube 84 is lowered so that its lower end is in the well 22, and pinch clamp 110 being tightened to close tube 106 and pinch clamp 112 be retracted to open tube 108, bulb 114 of bottle 102 is operated to produce a partial vacuum in said bottle to cause the red cells mixed with anti-coagulant to flow by suction into said bottle through tube 84, needle 116, Y-tube 104 and tube 108. In order to compensate for the volume reduction due to the removal of the plasma from the donor's blood, a suitable quantity of normal saline solution i. e. about 200 cc. is provided in bottle 102, preferably before the blood cells are removed to said bottle from vessel 10.

As soon as all the red cells are transferred from vessel 10 to bottle 102, in which they are mixed with the saline solution previously placed therein, the reinfusion operation is performed. In performing this operation, the tube 108 is disconnected from the Y-tube 104 and its outlet end is connected to the needle in the donor's arm, the stylet having been just removed as explained above. Bottle 102 is inverted and raised to a suitable level to allow the red-cell saline mixture to flow by gravity from the bottle to the needle and through the latter into the donor.

It will be understood that the plasma derived in accordance with the method and by the apparatus of the present invention can be processed in the usual way for its intended use.

The vessel 10 and the other parts of the apparatus can be easily cleaned and sterilized. In respect to vessel 10, it will be noted that access to the interior thereof is obtained through a comparatively wide top opening when cap 46 is removed. The caps 122 of bottles 100 and 102 are removable from the tops of said bottles so that the latter can be properly washed and sterilized. Similarly, the other parts of the apparatus can be readily cleaned and sterilized after each use and made ready for use in performing the blood separation and reinfusion process.

The vessel 10 is desirably of small size consistent with the quantity of blood centrifuged therein. By way of illustration but without limitation, it may be stated that a vessel having a diameter of about 7½ inches at the bottom of conical wall 16 and a diameter of about 2½ inches at the top of said conical wall and having a height of about 3½ inches measured perpendicularly between the base and upper end of said conical wall has been found in actual practice to give excellent results. The conical wall 16 is of advantage as it enables the vessel to be of small height and yet capable of retaining the blood therein during the centrifuging operation at high

speed without the blood tending to flow out of the vessel during the rapid rotation thereof. The tube 78 to which plates 74 extend is preferably comparatively small, say about 0.5 inch. It will be understood that plates 74 cause the blood in the vessel 10 to rotate therewith and thus improve the centrifugal action for separating the plasma from the red cells in vessel 10 in the centrifuging operation. It will be understood, however, that the chambers in vessel 10 between the plates 74 are in communication with each other through the spaces at the lower ends of said plates and that said chambers are in communication with the central part of the vessel below the bottom end of central tube 76.

While I have shown and described the preferred mode of practicing my invention various changes may be made therein. It is within the scope of this invention to withdraw the red cells from vessel 10 before the plasma is transferred from said vessel, and in such case tube 84 will be placed in communication with the layer of red cells and the latter removed by suction to bottle 102 while the plasma is still in vessel 10 where it can remain while the red cells are reinfused into the donor, and it will be understood that if this procedure is followed the plasma bottle 109 and the Y-tube 104 can be dispensed with, the tube 108 of bottle 102 being connected to needle 116. Other changes and adaptations of my invention will probably occur to skilled artisans in view of this disclosure and may be made without departing from the underlying idea of the invention with the scope of the appended claims.

Having thus described my invention, what I claim and desire to secure by Letters Patent is:

1. Apparatus for separating the plasma and red cells of blood from each other, comprising a centrifuge-vessel having an inlet for receiving the blood from the donor, said vessel being rotatable about a vertical axis and having a bottom inclined downwardly from the periphery thereof toward the axis of rotation whereby the blood and plasma flow toward the central part of said bottom and stratify in separate layers on said bottom after the centrifuging operation, and outlet means comprising a tube movably mounted in said vessel axially thereof to position the tube inlet at different distances from the bottom of said vessel to place said tube inlet in communication with the layers of plasma and blood cells, respectively, stratified by the rotation of said vessel, said tube having an outlet for the passage of said plasma or cells from said vessel.

2. Apparatus for separating the plasma and red cells of blood from each other, comprising a centrifuge-vessel having an inlet for receiving the blood from the donor, and outlet means comprising a tube movably mounted in said vessel to position the tube inlet at different distances from the bottom of said vessel to place said tube inlet in communication with the layers of plasma and blood cells, respectively, stratified by the rotation of said vessel, said tube having an outlet for the passage of said plasma or cells from said vessel, a stationary tube in said vessel axially thereof, said first mentioned tube being movable in said stationary tube, and a plurality of circumferentially spaced partition plates extending from the side wall of said vessel to said stationary tube.

3. Apparatus for treating blood of a blood donation, comprising a centrifuge-vessel in which the donor's blood is received and centrifuged for separating the plasma from the red cells, said vessel having a bottom, a conical side wall up-

standing directly from said bottom and converging upwardly therefrom, a tube disposed within said vessel axially thereof, said tube having a top opening, and a closure member removably mounted on said tube for closing said opening, said closure member having a needle-penetrable part to provide an opening in registry with the bore of said tube to receive a hollow needle in communication with said tube, for the admission of blood into said vessel and for the removal of the red cells therefrom following the centrifuging of the blood therein, said tube being vertically movable in said vessel to position its lower end adjustably near the bottom of the vessel.

4. Apparatus for treating blood of a blood donation, comprising a centrifuge-vessel in which the donor's blood is received and centrifuged for separating the plasma from the red cells, said vessel having a bottom provided with a central depression forming a well, said bottom having a part surrounding said well and sloping downwardly to said well, a discharge tube mounted in said vessel axially thereof and having its inlet end projecting into said well, said vessel having a top opening and a closure member for said opening, said tube extending through said closure member and having its upper outer end disposed externally of said vessel.

5. Apparatus for treating blood of a blood donation, comprising a centrifuge-vessel in which the donor's blood is centrifuged for separating the plasma from the red cells, said vessel being rotatable about a vertical axis and having a closed bottom whereby the plasma and red cells are disposed in different layers in the vessel at the bottom thereof after the centrifuging operation, when the vessel is stationary, a vertical tube adjustable to different levels adjacent the bottom of said vessel to communicate with the plasma and red cells in said layers, respectively, on the bottom of the vessel for removing the plasma and red cells from said vessel in separate constituent volumes, and means for applying suction to said tube.

6. Apparatus for treating blood of a blood donation, comprising a centrifuge-vessel in which the donor's blood is received and centrifuged for separating the plasma from the red cells, said vessel being rotatable about a vertical axis, and having a closed bottom, means for withdrawing the red cells from said vessel in a constituent volume thereof separate from the constituent volume of plasma, said means comprising a tube having its axis disposed axially of said vessel having one end thereof in communication with the interior of said vessel adjacent the bottom thereof and the other end thereof disposed externally of said vessel, said tube being adjustable to different levels adjacent the bottom of said vessel, and means for applying suction to said tube to cause the red cells to flow through said tube out of said vessel while the latter is stationary.

7. Apparatus for treating blood of a blood donation, comprising a centrifuge-vessel in which the donor's blood is received and centrifuged for separating the plasma from the red cells, said vessel having a closed bottom, a conical side wall standing from said bottom and having its larger end at said bottom, said bottom being inclined downwardly from said larger end of said side wall toward the axis of rotation to the center part of said bottom whereby the blood and plasma flow toward said center part of said bottom and stratify in separate layers on said bottom after the centrifuging operation, and a tube disposed within said vessel axially thereof and movably mount-

ed to position the tube inlet at different distances from the bottom of said vessel to place said tube inlet in communication with the layers of plasma and blood cells, respectively, stratified by the rotation of said vessel.
